UNITED STATES PATENT OFFICE

DOMENICO ANTONELLI, OF MANCHESTER, ENGLAND

ICE-CREAM CONE FORMING MACHINE

Application filed July 22, 1931, Serial No. 552,308, and in Great Britain August 7, 1930.

This invention refers to ice-cream cone forming machines wherein a plurality of heated mould units and a like plurality of mould cones are used, arranged in rows on 5 endless tracks and adapted to be moved intermittently along the tracks and to be transferred one by one from one portion of the track to another, the batter being supplied to the mould units at the commencement of their 10 movement along each of said portions of the track and the baked cones being discharged from the mould units on the latter completing their movement along such portions, the operations of filling, baking and discharging 15 being continuous.

The object of the invention is to provide an improved general construction of such machines, and in particular improved means for transferring the mould units and cores from 20 one side of the machine to the other, for raising the mould cores from the mould units prior to the baked cones being discharged, and holding same raised while being transferred from one side of the machine to the other, 25 and to provide means for lowering the mould cores after being so transferred. The invention also has for its object to provide improved means for unlocking the mould units and mould cores from each other prior 30 to their transference, and to improved means for relocking the mould units and mould cores after their transference.

Upon the accompanying drawings:

Fig. 1 is a side elevation of the machine 35 with some of the mould units and mould cores omitted, and with a portion of the outer track rail broken away. Further, certain parts are shown dotted in an alternative position.

Fig. 2 is a plan of the machine with some 40 of the core bars omitted.

Fig. 3 is a plan, on the same scale as Fig. 2, of the tracks upon which the mould units travel.

Fig. 4 is a like plan of tracks upon which 45 the inner ends of the mould core-carrying bars travel, while being transferred from one side of the machine to the other.

Fig. 4a is a plan of mechanism for unlock- 50 ing the cores.

Fig. 5 is a cross section of a core-carrying bar, and of a pair of mould units, the cores being shown raised clear of the moulds, which latter are formed by the half mould recesses in the adjoining faces of the two units. 55

Figs. 6 and 7 are detached side sectional and plan views respectively of the upper portions of the core-bar lifting mechanism.

Fig. 8 is a detached side elevation of the upper portions of the core-bar lowering 60 mechanism.

Fig. 9 is an edge view of such mechanism.

Fig. 10 is a side view of a part of the same mechanism.

Fig. 11 is an end elevation of one of the 65 core-bar transferring lever arms, and shows a side view of the mechanism on said arm for engaging the carrier bar or cross-bar of a core bar when transferring the latter from one side of the machine to the other. 70

Fig. 12 is a side elevation of the free end of the same lever arm, and an edge view of the cross-bar engaging mechanism.

Fig. 13 is an end view of the said arm, and a side view of a core-bar carrier bracket on 75 said arm.

Fig. 14 is an end view of one of the mould unit transferring arms and a side view of the mechanism on said arm for engaging a mould unit when transferring same from one side 80 of the machine to the other.

Fig. 15 is a side elevation of the free end of the same arm and an edge view of the said mould-unit engaging mechanism. In each view the mould units are shown in broken 85 lines.

Fig. 16 is an end elevation of the complete machine, and shows the end core bar on one side lowered, and the end core bar on the other side raised. Such view also shows the mechanism for unlocking the mould units and relocking them. 90

Fig. 17 is a plan of the end mould units and parts of the machine frame, and in particular the mechanism for locking, unlocking and relocking the mould units. 95

Fig. 18 is a front elevation of a part of the machine adjacent the point where the mould units enter a track, and such view shows 100

in elevation certain parts by which the unit locking levers are controlled.

As shown, the machine comprises the two vertical shafts 1, 1, one at each end of the machine, see Fig. 2, and receiving to and fro, or oscillatory motion through spur wheels 2, 2, and toothed racks 3, 3 on slides 4, 4, one of the slides being connected by link 5 to an eccentric or crank pin 6 of a driving wheel 7. The shafts 1, 1, are supported at their lower ends and along their length by bearing bosses 1^a, 1^b, forming part of the machine framing. Encircling the shafts are the fixed semi-circular flanges 8, which form part of the inner tracks for the mould units. Extending from flange to flange are L-section rails 9, 9, see Fig. 2, the rails and flanges forming a continuous track. Parallel with the rails 9, 9 are further L-section rails 10, 10, supported by the machine frame members 11, 11, such further rails and the rails 9, 9 forming parallel tracks upon which the mould units travel.

The mould units each comprise a bar 12 of rectangular cross section, in the vertical faces of which mould cavities or recesses are formed so that when two bars are placed side by side and the recesses in one come opposite those in the other, complete mould cavities are formed, see Fig. 5. The mould units are transferred one by one by mechanism hereinafter described, from one parallel track to the other. The mould units are of a length such as to cause them to extend from rail 9 to rail 10, on each side of the machine, and the number of mould units on each side of the machine is such as to completely fill the length of the track on that side, there being the same number of units on one side as on the other side of the machine, see Fig. 2.

Enclosing the shafts 1, 1, are further fixed flanges 13, 13 see Fig. 4, which lie above the flanges 8, 8, and form tracks for supporting the inner ends of the mould core carrying bars, while transferring same from one side of the machine to the other. There is a core bar for each pair of mould units, and each core bar comprises a hollow rectangular bar 14, from which depends a plurality of hollow mould cores 15, see Fig. 5, one for each mould cavity between the mould unit bars. Each core bar is suspended axially from a cross-bar 16 so as to be free to swivel about said bar, when necessary. At each end, each mould unit has a rod 17, which passes through an opening in the cross-bar and acts as a guide for the cross bar, when moved up and down. A roller 18 is fitted to each end of the cross-bar, and such rollers, on the cross bar approaching the discharge end of the tracks, engage mechanism by which the core bar is raised to cause its mould cores to lie clear of the mould units, preparatory to the endmost mould unit being unlocked and the baked cones discharged therefrom, and also

preparatory to the endmost mould unit and core bar being transferred to the entrance end of the tracks on the other side of the machine.

Each core bar is normally held locked to its mould units by a hook-like lever 19, pivotally mounted on the cross bar 16, and engaging a complementary hook-like shoulder 20 on the mould units, springs 21, between the cross bar and core bar, see Fig. 16, allowing the levers to engage and hold the parts together with a slightly yielding pressure.

On each end of each mould unit are two lugs 22, 22, each of which when the adjacent units lie close together, lies against a like lug on the next unit, and by means of such lugs and fork-ended levers 23 pivotally mounted on a further lug 24 of the mould unit, the units are adapted to be held firmly one alongside the other, each of the levers 23 normally engaging the lugs 22 under the force of a spring 25 acting as between the lower end of the lever and a bracket 26 below the unit, see Fig. 16. On each mould unit reaching the end of its traverse along one side of the machine, the locking levers 23 of such unit are operated to release the unit by means of cams. One of such cams forms part of a slotted lever 27, see Fig. 16, which by means of a pin 28 in a vertical slide bar 29 moving upwards and entering the inclined part of the slot, moves about its pivot to a position where it lies in the path of the small roller 23^a on the lower end of the lever 23, and as the endmost mould unit moves forward, offers an obstruction thereto, and produces the desired angular movement of the lever 23 to release the end mould unit, at that end, from its neighbour.

The other cam is in the form of a fixed semi-circular flange 30 surrounding the shaft 1, against which flange the small roller 23^a at the lower end of the lever 23 on the inner end of the mould unit bears, the two cams thereby releasing the endmost unit from the next unit.

The bar 29 at each end of the machine is raised and lowered at the proper time by inclined track cams 31 on the slides 4, 4, the bar having a bowl 29^a to travel in the cam groove.

The raising of the core bars 14, preparatory to unlocking the endmost mould unit to discharge the baked cones, and transfer the mould unit to the other side of the machine, is effected partly by means of fixed brackets 32, 32, one at each side of each track, and each having an inclined upper part, see Figs. 1 and 6, on to which the rollers 18 of the cross bars pass as they reach the end of the traverse of the mould units and core bars, and just after the end core bar has been released from the mould units by the lower hook-like end of the lever 19 moving outwards and clear of the hook-like shoulder 20 on the mould unit. The means for effecting

such release of the lever 19 is hereafter described. The further raising of the end mould core bar is effected by the vertical bar 29, at each side of the track having at its top end a plate 33, which on its underside carries a further plate 34, normally lying level on its top face with the top horizontal part of the upper face of the adjacent bracket 32. On the cross bar rollers passing on to the plates 34 at each side of the track, the bar 29 is then raised by the inclined cam tracks 31 of the slide 4 immediately below the mould units on the same side of the machine until the plate 34 of each bar lies level with the top face of a further fixed bracket 35 at one side of the track and with the top face of the flange 13 at the other side of the track. Simultaneously with the arrival of the cross-bar 16 at the said raised level, the bar is caught by the mechanism hereafter described, for transferring it to the other side of the machine. While being raised and moved forward the end core bar 14 is tilted about its axis, to cause the cores to move clear of the baked cones and facilitate their discharge from the moulds as the mould units are separated. Such tilting of the end core bar is effected by means of a small bent arm 36 at one end of the cross bar (see Fig. 16) meeting an abutment 37 on the bracket 38 and wiping past such abutment as shown by the broken lines in Fig. 6. The spring 14^a acting between the core bar 14 and the cross bar 16 assists in returning the cores to the vertical position, and a roller 14^b on the core bar, meeting the bar 17, limits the return of the core bar.

The means used for releasing the core bars from the mould units consists of a plunger rod 39 at each side of the track and below the bottom ends of which the rollers 18 on the cross bar 16 pass, at which moment the plunger rods are depressed by means of lever arms 40 carried by a cross shaft 41 and by means of a further lever arm 42 on said shaft, which, in turn, receives movement from the mechanism used for transferring the end core-bar to the other side of the machine. To ensure of the levers 19 leaving the shoulders 20 when the core bars are depressed, a spring pressed finger 19^a is provided, against which each lever 19 bears and by which it is moved clear of the shoulder 20 as the core bar moves forward.

The mechanism for transferring the core bars from one side of the machine to the other will now be described.

Secured to each of the vertical shafts 1, 1 is a pair of long lever arms 43, 44, the lower lever arm 43 being adapted to engage and transfer the endmost mould unit when such unit is timed to be taken to the other side of the machine, and the upper lever arm 44 being adapted to engage and transfer the end-

most core bar and cross bar when requiring to be taken to the other side of the machine.

As shown by the broken lines in Fig. 1, the inner end of the mould unit, while being transferred, is carried upon the track plate 8, and the inner end of the cross bar 16 is carried by the flange 13. The outer end of the mould unit is carried by the lever arm 43, which is furnished with a bracket 45 with bevelled cross head, upon which the mould unit rests, see Figs. 14 and 15.

Each mould unit, between the mould cavities, is hollow, forming flue passages for the heating medium, and the front and rear walls of the passages, are used to effect the transference of the units. That is to say, pivotally mounted on one side of the lever arm 43 is a metal bar 46 with inclined upper extremity, which is normally held raised by a spring 47. On the lever arm 43 moving across the machine, the inclined extremity of the bar 46 meets the outer lower edge of the mould unit and then moves down to pass below said edge, after which, on coming below the unit, it moves up again, and thereby becomes engaged with the unit. On the other side of the lever arm 43 is a further pivotally mounted and spring-held bar 48, with bent upper end extending towards the bar 46, and the nose of the bar 48 then lying close to the mould unit, which is thereby held relatively to the lever arm 43, and is ready to be transferred to the other side of the machine. On such transfer taking place, the plate 46 pushes against the unit which is thereby caused to move with the lever arm to the other side of the machine.

On the bevelled edge of the upper end of the bar 48 meeting the last transferred mould unit, it is depressed, and held depressed by the final movement of the mould unit carried by the lever arm. On the lever arm then making its return or idle movement, the inclined upper end of the bar 46 meets the other lower edge of the mould unit, and owing to the unit being then held against return movement, as hereinafter explained, slips below the said edge, the bar 48 by that time being below the mould unit last transferred, see Fig. 14, when the lever arm is free to return to the starting point to engage and transfer the next mould unit, the bevelled upper end of the bar 46 engaging such next unit by passing below it and upwards into the flue passage.

The bars 46, 48 are held to the lever arm 43 by links 49, which are pivoted to a plate 50 clamped to the lever arm. The upward movements of the bars 46, 48 are limited by pins 51.

Each cross bar and core bar is transferred simultaneously with a mould unit, by the lever arm 44, which has a hook-like bracket 52 at its free end, see Figs. 12 and 13, with which the hook-like part 14^a of the core bar engages when the lever arm moves to engage the cross bar. On the lever arm 44 are pivotally

mounted gravity fed bars 53, 54 the lower end of the bar 53 being inclined, in order that it may ride over the cross bar, when moving to engage same.

5 The bar 54 at its lower end extends towards and away from the bar 53 and the front and rear edges of such end are bevelled. As the lever arm 44 moves to engage a cross bar, the bar 53 rides over and then drops behind it, 10 while the lower end of the bar 54 lies opposite the cross bar, see Fig. 11. The lever arm is then moved to transfer the cross bar and with it the core bar to the other side of the machine, on reaching which, the bar 54 meets and rides 15 on to the preceding cross bar, and in such position allows the cross bar, then being transferred, to pass into the correct position for subsequent lowering and passing forward. On the lever arm 44 making its return movement, the bar 54 rides off the last transferred cross bar, and resumes its original position, ready to co-operate with the bar 53 in engaging and transferring the next cross bar. As 20 the lever arm 44 moves back to its original position, a projection 55 on the lever arm meets and presses against the lever arm 42 on the cross shaft 41 and depresses the plunger rods 39 by which the cross bars prior to running on to the inclined brackets 32 are 25 pressed down against the springs 21 to release the latching levers 19, which by means of the finger 19a previously described are moved clear of the shoulders 20 to unlatch the core bars from the mould units. To prevent the 30 mould units rebounding or moving back on reaching the other side of the machine, that is, on reaching the entrance of a track, a hook 56 is provided, under the bevelled end of which the stud of the roller of the mould unit 35 passes and which engages the roller stud to prevent its backward movement.

On reaching the opposite side of the machine, the roller 18 on the cross bar comes to rest upon plates carried at the upper ends 40 of the link bars, designed to be lowered until the core bar and its cores engage the mould units, there being lowering mechanism on each side of the track. Such lowering mechanism, which for each side of the track is 45 shown at the right hand end of Fig. 1, and in Figs. 8, 9 and 10, comprises the link bar 57, with an angle-iron plate 58 on one side of its upper end, the link bar being pivoted at its lower end to a vertical rod or bar 59, which at its lower end engages, by a bowl 50 60, an inclined cam track 31 on the slide 4.

Alongside the bar 59 is a fixed slotted plate 61, the slot in which has two parallel vertical parts and two parallel inclined parts, produced by an island piece 61a. In the slot works a pin 62 carried by a further link bar 63 pivoted by short links 64, 64 to the link bar 57.

65 To the upper end of each cam bar 59 is fitted a horizontal plate 65 which overhangs

the cross bar roller 18 when such roller is resting upon the plate 58 (see Figs. 8 and 9) so that in lowering the link bars 57, 63 by means of the cam bar 59 to lower the cross bar, the plates 58, 65 compel the cross bar rollers to move down also. On the core bar reaching its lowest position, i. e. resting upon the mould units the cam bars 59 commence to rise up again, the cam 31 having then reversed its direction, and in order to cause the plates 58 of the link bars 57 to pass from beneath the cross bar rollers 18 before rising, so as not again to raise the core bar, the pin 62 in the cam slots 61b of the plates 61 causes the plates 58 to be drawn from below the rollers (to the right in Fig. 8) during the latter portion of the descent of the cam bars as shown in Fig. 1, and owing to the cam slot 61c and to ascend in a path in which they remain clear of the rollers, and finally resume their original positions, shown in Figs. 8 and 9, immediately behind the cam bars, and level with the fixed parts of the track or bracket 18 on to which the rollers run when transferred from the other side of the machine.

The endmost mould unit, after meeting the last transferred mould unit, is locked to such unit by means of the levers 23 and lugs 22. The levers are moved and held out of engagement with the lugs 22 during the latter part of their being carried from one track to the other and until the mould units are in correct position for relocking by means of cams, one of which is in the form of a swelling 30a on the fixed flange 30 and the other in the form of a flat-sided metal bar 66 slidably mounted in a bracket 67 against the resistance of a spring 68, see Figs. 17 and 18. As a mould unit passes from one side of the machine to the other, the lower end of the lever 23 at the inner end of the unit, engages the cam swelling 30a on the flange 30, and thereby holds the forked end of the lever clear of the lugs 22 on the unit until the unit is in contact with the preceding unit. Similarly, the lower end of the lever 23 at the outer end of the mould unit, meets and presses against and travels over the face of the bar 66, and the forked end of the lever 23 is thus held clear of the lugs 22 on the units.

When, however, the next mould unit is brought round to that part of the machine, the previously brought unit is moved along the track to a position where the inner roller 23a leaves the cam swelling 30a so that the inner lever 23 locks the units together. As the radial arm 43 now commences its return movement (to the right in Fig. 18) a plate 69 thereon meets a trip lever 70 on a bell-crank lever 71, see Figs. 16, 17 and 18, and moves such lever 71 about its pivot, and by means of the rod 72 retracts the bar 66 out of contact with the roller 23a.

so that the lever 23 may regain the locking position. The spring 68 serves normally to keep the bar 66 in position for actuating the levers 23, although it cannot regain that position to unlock the units once the mould unit has passed. The trip lever 70 and its spring 70^a permit the arm 43 to pass in one direction, i. e. the mould transferring direction, without influencing the bar 66, see Fig.

10 18. The new batter is delivered to the mould units immediately they are locked together, and before the mould core bars are lowered.

15 After a core bar has been lowered on to the mould units, it passes forward along with them and becomes relocked to the mould units by means of the levers 19 and shoulders 20, the rollers of the cross bar coming below a pair of presser bars 73, which are operated to depress the cross bars against 20 the springs 21, there then being no support under the rollers 18, by a cam swelling on a disc 74 on the adjacent vertical shaft 1, and by levers 75 on a cross shaft 76 which also carries lever arms 77 connected at their outer 25 ends to the presser bars 73. The lever arm 75 has a bowl 75^a to engage the cam, and is kept in engagement by a spring 78. As the cam 74 rotates, the levers 75 and 77 are rocked and the presser bars 73 depressed, 30 whereupon the levers 19 fall by gravity into the locking position.

35 The mechanism for delivering and controlling the batter comprises the pivotally mounted feed pipes 79 which are moved clear of the incoming core bars and moulds by means of the reciprocating slides 80 connected to the slides 4, a pin 80^a on the bar 80 working in a slotted arm 79^a on the axis of the pivotally mounted feed pipes 79. The mould 40 units are advanced along the tracks step-by-step by the pawls 81 on the pivoted lever 82, which is connected by the rod 83 to further pivoted arms 84, adapted to be moved about their pivots by the slides 4, upstanding projections 85 on the slides 4 engaging rollers on the lower ends of the levers 84. The pawls 81 are timed to engage the last transferred mould unit just prior to the radial arm 43 commencing its return movement.

50 The machine illustrated is fitted with fast and loose belt pulleys 86 to receive power, which is transmitted by shaft 87, bevel gears 88 and pinion 89 to the wheel 7.

55 The cones are baked whilst the mould units pass along the tracks over gas burners 90 supplied with gas from pipe 87 along the sides of the machine.

60 It will be understood especially from a consideration of Fig. 2, that the mechanism at one end of each track of the machine is a replica of the mechanism at the end of the track diagonally opposite, or that one half of the machine, taken to right or left of a line drawn through the shafts 1, 1 is a duplicate of the other half, the inlet end of one

half of the machine being next to the outlet end of the other half of the machine.

What I claim is:—

1. A machine for making ice-cream cones by the progressive movement of mould units along a track, with means for automatically coupling and separating the mould units, for inserting and removing cores, for feeding batter to the moulds and for baking; comprising two straight lengths of track parallel with each other, a vertical shaft at each end of the tracks, two radial arms on each shaft, means at one end of each track for raising the cores from the moulds, and at the other end of each track for lowering the cores into the moulds, means on the uppermost arm to engage with the cores, when raised and carry them, series by series, from one length of track to the other, means on the lowermost arm to engage with the mould units and carry them one by one from one length of track to the other, and means to oscillate the shafts and arms so that successive mould units and their cores are transferred from one length of track to the other, as set forth. 70

2. A machine for making ice-cream cones as claimed in claim 1, comprising two straight lengths of track parallel with each other, semi-circular flanges on the vertical shafts forming continuations of the inner rails of the tracks, and also forming supports for the inner ends of the mould units whilst being carried from one track to the other, and further semi-circular flanges on the vertical shafts above the first named flanges, forming 90 a support for the inner end of the series of cores when raised and whilst being carried from one track to the other, as set forth. 95

3. A machine for making ice-cream cones as claimed in claim 1, comprising mould units any two of which when placed together produce a series of moulds, lugs on each end of the mould units, a pivoted locking lever on each end of each mould unit, a spring for holding each lever normally in the position for embracing the adjacent lugs of consecutive mould units to lock the units together, a stationary cam on each of the vertical shafts to engage the locking levers on the inner ends 100 of the mould units and unlock them prior to and whilst being transferred by the radial arms from one track to the other, a pivoted cam lever at one end of each track opposite the stationary cam, which, when in one position, lies in the path of the locking levers on that end of the mould units, and causes the latter to release the endmost mould unit 110

and to hold it free until engaged by the radial arm, the said cam lever being moved out of the path of the locking levers as soon as the endmost mould unit is released and is moved away; a spring-controlled slidable bar adjacent the entrance end of each track with which the locking lever at the outer end of the mould unit engages and by which it is 120 125 130

held clear of the lugs on arrival at such end of the track, and a trip lever by which and the radial arm, the said slidable bar is moved to release the locking lever so that it may engage the lugs to lock the mould unit to that already in the track, as set forth.

4. A machine for making ice-cream cones as claimed in claim 1, comprising a cross bar carrying the cores for each mould unit, a pair of fixed brackets near the outlet end of each track, said brackets having inclined upper faces with which the cross bar engages on approaching said end of the track, vertical bars adjacent said fixed brackets, each bar having a lateral plate or shelf which normally lies level with the higher part of the inclined upper face of the adjacent fixed bracket, and on to which the cross bar passes after leaving the bracket; a further pair of fixed brackets or short-track plates above the first-named brackets, a reciprocating slide below the mould unit track, upstanding flanges with inclined cam grooves on said slide, with which the said vertical bars engage, and means for reciprocating the slide, and thereby causing the vertical bars to rise and raise the cross-bar to the level of the upper fixed brackets, as set forth.

5. A machine for making ice-cream cones as claimed in claim 1, comprising a cross bar carrying the cores for each mould, a pair of fixed brackets with inclined upper faces near the outlet end of each track, vertical bars adjacent said fixed brackets, each bar having a lateral plate or shelf which normally lies level with the higher part of the inclined upper face of the adjacent fixed bracket, and on to which the cross bar passes after leaving the bracket, a further pair of fixed brackets, or short-track plates above the first-named brackets, a reciprocating slide below the mould unit track, upstanding flanges with inclined cam grooves on said slide, with which the said vertical bars engage, means for reciprocating the slide, a pair of lever arms on each of the vertical shafts, means on said arms for engaging the endmost mould unit and the said raised cross bar and carrying same from one track to the other, and means adjacent the entrance end of the tracks for detaining the mould unit and cross bar, and releasing same from the lever arms as set forth.

6. A machine for making ice-cream cones, comprising two vertical shafts one at each end of the machine, forward and return tracks between the two shafts, mould units on the tracks, radial carrier arms on the shafts for transferring the mould units one by one from the forward to the return track, a support on the radial arms for the outer end of the mould unit, spring-controlled pawls on the carrier arms to pass beneath the mould unit to be transferred and push it as the radial arm moves forward, and guide members on the

radial arms lying before the mould unit then being transferred until depressed from before such unit by engagement with the previously transferred unit, as set forth.

7. A machine for making ice-cream cones, comprising two vertical shafts one at each end of the machine, forward and return tracks between the two shafts, mould units on the tracks, radial carrier arms on the shafts for transferring the mould units one by one from the forward to the return track, a support on the radial arms for the outer end of the mould unit, spring-controlled pawls on the carrier arms to pass beneath the mould unit to be transferred and push it as the radial arm moves forward, and guide members on the radial arms lying before the mould unit then being transferred until depressed from before such unit by engagement with the previously transferred unit, core bars in the mould units, cross bars carried by the core bars, further radial arms on the vertical shafts for transferring the core bars from one side of the machine to the other, a hook member on the said further radial arms to support the outer end of the core bar, gravity controlled, pawls on the said further radial arms to pass beneath the cross bar to be transferred and push it as such radial arm moves forward, and guide members on the further radial arms lying before the cross bar then being transferred until raised from before the cross bar by engagement with the last transferred cross bar, as set forth.

8. In an ice-cream cone forming machine as claimed in claim 1, a cross bar carrying the series of cores for each mould unit, pivoted mould latching levers on the cross bar, vertical presser bars or plungers near that end of each track where the cross bars require to be raised to hold the cores clear of the mould units, a shaft extending across the track and above the mould units and cross bars, a pair of lever arms on said shaft pivotally connected with the presser bars, a third lever arm on said shaft and a projection on the cross-bar transferring lever arm, which presses upon the third lever arm to operate the presser bars and release a latching lever when the core-bar-transferring lever arm is about to engage the cross bar and the spring pressed finger in the path of the released latching lever, as set forth.

9. In an ice-cream cone forming machine as claimed in claim 1, cross bars carrying the series of cores for each mould unit, pivoted mould latching levers on the cross bars, vertical presser bars or plungers at that end of each track where the cross bars require to be relocked to the mould units after being transferred, the lower ends of the plungers lying immediately above the ends of a cross bar, a disc with cam swelling on its edge, on the adjacent vertical shaft, and a lever and spring through which the disc acts to de-

press the plungers and the cross bar below same, to allow the latching levers to assume the locking position, as set forth.

10. In a machine for making ice-cream cones as claimed in claim 1, means for lowering the cores into the moulds comprising vertical bars to each of which is pivoted a short lever arm with horizontal flange, the arm being normally parallel with the bar and the flange being at its upper end, fixed brackets or track plates adjacent the upper ends of the vertical bars with which brackets or plates the flanges of the lever arms normally lie level, the cross bar, when brought from the other side of the machine, first passing on to the brackets and then on to the flanges of the lever arms, a slotted fixed plate near the upper end of each vertical bar, a further lever arm connected by links to each 20 vertical bar and lying parallel therewith, its upper end engaging the slot of the adjacent slotted plate, upstanding flanges on a reciprocating slide below the tracks with inclined cam grooves and with which the said vertical bars engage, reciprocation of the slide causing the vertical bars to descend or to ascend, the flanges of the short lever arms, by reason of the slotted plates and the further lever arms linked thereto being caused to pass from 25 below the cross bar and finally return to their original positions ready to receive and lower the next cross bar, as set forth.

In testimony whereof I have signed my name to this specification.

35 DOMENICO ANTONELLI.
